UNITED STATES PATENT OFFICE.

STANISLAS ZYLBERLAST, OF MANCHESTER, ENGLAND.

DOUBLE-ACTING PUMP.

No. 806,388.

Specification of Letters Patent.

Patented Dec. 5, 1905.

Application filed April 22, 1905. Serial No. 256,972.

To all whom it may concern:

Be it known that I, STANISLAS ZYLBERLAST, engineer, a subject of the Emperor of Russia, and a resident of 409 Stretford road, Old Trafford, Manchester, in the county of Lancaster, England, have invented a new and useful Improvement in Double-Acting Pumps, of which the following is a specification.

This invention relates to double-acting pumps for gases and liquids.

The principal object of this invention is the provision of a double-acting pump which is especially adapted for employment in conjunction with a condensing apparatus of any description—for example, any of those used for obtaining vacuum in steam-engines, turbines, and chemical apparatus—and affords advantages in action and in efficiency and simplicity in construction not attained in pumps hitherto available for such purposes as aforesaid and may, as will be hereinafter explained, be constructed without suction-valves.

According to this invention a double-acting pump is provided with a hollow cylinder or bucket made to work externally in a working surface provided in the pump-casing and internally upon a fixed cylinder supported in any suitable way, so that in the operation of the pump the space left or formed outside the hollow cylinder or bucket and within the pump-casing and the space left within the hollow cylinder or bucket form two working spaces, which enable each stroke of the hollow cylinder or bucket to expel fluid and so make the pump double-acting, and can be utilized in the manner which may be most effective for the purpose for which the pump may be intended—as, for example, by one space being used wholly or principally for gaseous fluid, while the other is used wholly or principally for liquid, or so that both spaces may be used alike—as, for example, both for gaseous fluid or both for liquid or both for mixtures of gaseous fluid and liquid—and may be constructed to be arranged vertically or in a horizontal or other desirable position.

According to this invention, in the form which will be described first by way of illustration, a hollow cylinder with its top end open is made to work tightly in an outer working surface within the pump-casing—as, for example, in a liner fixed therein. On the inside this cylinder passes and works over a shallow cylinder fixed in any suitable manner within the pump-casing—as, for example, by being connected by arms to any suitable part—

and receives thus another working surface, which is made air-tight in any ordinary way. In the pump-casing are furnished partitions which, together with the body whereon the outer working surface is formed, divide the casing into two separate chambers and form receptacles for directing the fluids to be pumped into the inside and outside of the working cylinder or bucket. The outer working surface is provided with a suitable number of ports—as, for example, by being formed with rows of holes or by being formed in two or more parts, so that between each part and its neighbor a continuous circumferential opening is left—and these ports are provided in such positions that one allows the medium to be pumped to flow below the working cylinder as soon as it passes such port on its upward stroke, while another opens communication with the inside of the working cylinder when a corresponding provision for the passage of fluid—as, for example, a row of openings around the working cylinder—comes in line with the said port on the downward stroke of the working cylinder or bucket. On its upward stroke the cylinder or bucket may discharge fluid through valves fixed in a suitable position—as, for example, in the hollow cylinder hereinbefore mentioned—and on its downward stroke may discharge fluid through valves fixed in suitable positions—as, for example, at the bottom of the pump.

Pumps constructed according to this invention are especially adapted for work in conjunction with condensing plants of any description—such, for example, as those used for creating vacuum in steam-engines, turbines, chemical apparatus, and in apparatus of other kinds—and a pump of this kind can be used as a combined dry-air pump and water-pump in one unit, one part of the bucket dealing with the air only and the other dealing with the water, either circulating or condensed. Pumps constructed according to this latter form are suited admirably for mill-engines, as in such a pump the pump-casing may be shaped in such a way as to form a jet-condenser around the pump and to have the overflow-water conveyed direct into the top part of the same, so that the pump forms a complete counter-current jet-condensing plant in one single unit, thus making it possible to do away entirely with the highly-uneconomical parallel-current condensers.

In the accompanying drawings, which are diagrammatic, and in all the figures of which

the same characters of reference are employed to indicate corresponding parts, Figure 1 is a vertical section taken on the plane indicated by the line A A of Fig. 2, illustrating a pump 5 constructed according to the first hereinbefore-described form of this invention; and Fig. 2 is a plan of the said pump with the upper cover of the pump-casing removed, these figures illustrating a pump intended specially 10 for use in pumping either gas alone or gas with only a very small admixture of liquid. Fig. 3 is a vertical section taken on the plane indicated by the line B B of Fig. 4 of a pump used as a combined dry and wet pump, and 15 Fig. 4 is a plan of such pump with the upper cover of the pump-casing removed, these figures illustrating one way of applying a pump constructed according to this invention in conjunction with a jet-condenser. Fig. 5, which 20 is a vertical section of the pump taken on the plane indicated by the line C C of Fig. 6, and Fig. 6, which is a plan of such pump with the upper cover of the pump-casing removed, show a modification of the pump shown in Figs. 1 25 and 2, which may be used as a dry pump only or a wet pump only. Fig. 7, which is a vertical section of a pump taken on the plane indicated by the line D D of Fig. 8, and Fig. 8, which is a plan of such pump with the upper 30 cover of the pump-casing removed, represent the combination of a pump constructed according to this invention, generally in the manner illustrated in Figs. 3 and 4, with a counter-current jet-condenser largely cast 35 with a pump-casing in a single unit.

In Figs. 1 and 2 *a* is the hollow cylinder with its top end open, and *b* is a liner in which the cylinder *a*, which forms a piston or bucket, is made to work tightly in any suitable way. 40 The liner *b* is shown as made to fit in the pump-casing *c*, which is provided with a cover *d*, fitted tightly thereon, and is formed with three partitions *e f g*, which are shown as formed on the casing *c* and are furnished with 45 central openings to receive and fit tightly around the liner *b*. The liner *b* is secured to the upper partition *e*. Internally the cylinder *a* is made to move upon a shallow cylinder *h*, fixed securely to the pump-casing *c*, arms *i*, 50 formed upon and extending from the cylinder *h*, being secured to projections *j*, formed on the interior of the pump-casing *c*. The cylinder *a* is made air-tight around the shallow cylinder *h* by any suitable means. The lower 55 partition *g* is shown as provided with downward extensions made to fit upon the inner edge of a flange *k*, formed around the upper part of the base *l* of the pump. The partitions *e f g*, acting in conjunction with the flange 60 *k*, and the liner *b*, divide the space within the casing *c* and below the cover *d* into four compartments—namely, two inlet-channels *m' m²*, 65 communicating with an opening *n*, by which the medium to be pumped may be admitted to the pump, and two receptacles *o p*, provided

with outlet-openings *q r*, respectively, by means of which the medium pumped may be discharged from the pump. At its lower part the base *l* is provided with an opening and closed by a plate *s*, secured to it and internally 70 of a shape corresponding to that of the lower face of the cylinder or bucket *a*, which is shown as formed conical, so as better to deliver liquid in the manner now well known, and is connected to a piston-rod *t*, passed through glands or stuffing-boxes *u v*, provided, respectively, on the cylinder *h* and cover *d*, and is guided in any suitable manner, so as to be incapable of allowing the cylinder *a* to be turned about its center line. Provision is made 75 in any suitable manner for the communication of the working space—namely, the space below the cylinder or bucket *a* and the space within such cylinder or bucket *a* with the channels *m' m²* in the pump-casing *c*. In the case 80 illustrated the liner *b* is provided with openings *w' w²*, arranged in two rows. By means of the lower rows of openings *w'* the channel *m'* is placed in communication with the interior of the liner *b*, so that the medium to be 85 pumped may pass below the cylinder or bucket *a* when such cylinder or bucket *a* is raised high enough to uncover the openings *w'*, and by means of the upper row of openings *w²* the channel *m²* is placed in communication with the 90 interior of the said cylinder or bucket *a* above the bottom thereof, so that the medium to be pumped may enter the interior of the cylinder or bucket *a* when it is depressed low enough for 95 openings *x*, provided in the cylinder or 100 bucket *a*, to come into communication with the openings *w²*. The shallow cylinder *h* is shown as provided with valves *y*, made to open upward and arranged in conjunction 105 with seatings and guards in any manner usual or suitable for air-pump valves, so that in the upward movement of the cylinder or bucket *a* the air or water in the interior of the cylinder or bucket *a* may be discharged past the valves *y* into the shallow cylinder *h*, whence 110 it flows through the openings *x* or, eventually, over the top of the cylinder or bucket *a* to the upper outlet *r* and so out of the pump. The base *l*, to which the pump-casing *c* is connected by suitable means, is shown as provided 115 with valves *z*, made to open upward into the receptacle *p* and arranged in conjunction with seatings and guards in any manner usual or suitable for air-pump valves, so that in the downward movement of the cylinder or bucket *a* the air or water beneath such cylinder or 120 bucket *a* will be discharged past the valves *z* into the receptacle *p* and so to the lower outlet *q* and so out of the pump.

The pump illustrated by Figs. 1 and 2 is 125 intended especially for use in pumping either gas alone or gas with only a very small admixture of liquid, and in pumping gas with a small admixture of liquid will deliver gas alone or gas with very little liquid at the up-130

per outlet r , and the liquid or the liquid with a proportion of gas at the lower outlet q , the partition f serving to separate, more or less, the liquid from the gas at their entrance to the interior of the pump. The partition f becomes of special importance when a pump constructed according to this invention is used as a combined dry and wet pump, as it then separates entirely the air from the water, the air being then discharged by the upstroke of the cylinder or bucket a and the water on the downstroke, or vice versa. Although in this way of using a pump it is preferable that the overflow-water from the condenser shall be delivered into the lower chamber of the pump and that the air shall be delivered into the higher chamber, the water may be delivered into the higher chamber and the air into the lower.

In the pump illustrated in Figs. 3 and 4, which is in general construction similar to that illustrated in Figs. 1 and 2, the lower channel m' is made to communicate with a pipe l , by which the liquid to be pumped is led to the pump and through the one set of openings w' , formed in the liner b into the working space below the cylinder or bucket a when such cylinder or bucket a is raised high enough, while the upper channel m^2 is shown as made to communicate with an inlet 2 for the air to be pumped, and is also shown as made to communicate through the openings w^2 , formed in the liner b with the working space in the interior of the cylinder or bucket a when depressed low enough for the openings x therein to come into communication with the openings w^2 .

In the pump illustrated in Figs. 5 and 6, which in other respects is generally similar to that illustrated in Figs. 1 and 2, the partition f is dispensed with, so that only the inlet-channel m is provided, and instead of two rows of openings w' w^2 one row of openings w is employed, or instead of the openings w being formed in the liner b the liner b might be made in two parts fixed at a suitable distance apart in the pump-casing c , so as to leave a circumferential opening between them.

Figs. 7 and 8 represent the combination of a pump constructed according to this invention, generally in the manner illustrated in Figs. 3 and 4, with a counter-current jet-condenser largely cast with the pump-casing c in a single unit. In the pump illustrated by Figs. 7 and 8 the counter-current jet-condenser is constituted by a cavity 4 in the pump-casing c , which is made to receive steam to be condensed and any air or other gas which may accompany it through an inlet 5, which cavity 4 is situated below a perforated partition 6, formed at the bottom of a channel 7 in the pump-casing c , which is in communication with a pipe 8, by means of which water or other liquid to be used as the condensing agent is supplied to the said channel 7.

The channel 7 is shown as made to extend for a convenient distance around the casing c and is shown as closed above by means of part of the cover d , and the cavity 4 is shown as made to extend around the casing c for a somewhat greater distance than the channel 7 and is shown as bounded at one end by a partition 9, which does not reach quite to the cover d , so that the air or other gas may pass from the cavity 9 over the partition and down a channel 10, formed in the casing c , to the upper channel m^2 . The action of the pump illustrated in Figs. 7 and 8 being similar to that of the pump illustrated by Figs. 3 and 4, it is obvious that it will induce steam and air or other gas entering by the inlet 5 to tend to rise through the cavity 4 toward the upper end of the partition 9 in a direction more or less contrary to that in which water or other condensing liquid supplied through the channel 7 falls from the partition 6.

In the pump illustrated by Figs. 7 and 8, as in that illustrated by Figs. 3 and 4, although it is preferable that the overflow-water from the condenser shall be delivered into the lower chamber of the pump and that the air or other gas shall be delivered into the higher chamber of the pump, the water may be delivered into the higher chamber and the air or other gas into the lower chamber.

The cylinder or bucket a of the pump illustrated by Figs. 3 and 4 and the cylinder or bucket a of the pump illustrated by Figs. 7 and 8 are reduced in diameter for a little distance at the parts 11 at the lower circumferences, so that when at the highest part of their strokes the said cylinders or buckets shall allow the channel m' m^2 to be in communication, so that any inequality of pressure in the channels m' m^2 used with either of such cylinders or buckets a which might interfere with the proper flow of liquid into the pump may be equalized.

The pumps illustrated in Figs. 1 and 2, Figs. 3 and 4, Figs. 5 and 6, and Figs. 7 and 8 are provided with hand-holes furnished with removable covers 12 where necessary, so that access to the valves y z and other parts of their interiors may be obtained.

A partition like the partition f to separate channels for the admission to a pump of air or other gas and of water or other liquid, respectively, may be applied in pumps other than those hereinbefore described for purposes similar to those hereinbefore described.

In double-acting pumps hitherto made, in which the inlet for the fluid to be pumped is in the midway of the strokes of the pistons or buckets, the efficiency of each stroke is wasted to the extent of one-half, so that the volumetric efficiency is only fifty per cent., whereas in pumps constructed according to this invention no part of the stroke of the plunger or bucket or piston is wasted.

Modern investigations into the action of

condensing apparatus have proved amply that for equal duty a parallel-current condenser requires considerably larger displacement in the pump used with it than a counter-current condenser. Nevertheless, parallel - current condensers are still in extensive use because of the compactness of the apparatus and because for a parallel-current condenser only one wet-air pump is required as against a separate dry-air pump and a separate water-pump, which are necessary for a counter-current condenser as hitherto constructed. By dividing a pump constructed according to this invention in the manner hereinbefore described, so that air shall be dealt with by the stroke of the piston or bucket in one direction, while the overflow-water is dealt with by the stroke of the piston or bucket in the other direction, the necessity for two different pumps is entirely obviated, and thus the use of parallel-current condensers is now no longer justified.

From the foregoing description it is obvious that double-acting pumps constructed according to this invention are simple in construction and advantageous and efficient in action and are especially adapted for employment in conjunction with condensing apparatus of any description—as, for example, any of those used for obtaining vacuum in steam-engines, turbines, and chemical apparatus—and may be constructed without suction-valves.

What I do claim, and desire to secure by Letters Patent, is—

1. In a double-acting pump, the combination of an internal working surface upon a fixed part adapted to permit passage of fluid to be pumped, an external working surface upon another fixed part, a hollow cylinder or bucket fitted upon the said external working surface and in the said internal working surface to work on and in such surfaces respectively and adapted to allow fluid to enter it and means to allow fluid pumped to issue from the interior of such cylinder or bucket, substantially as hereinbefore described.

2. In a double-acting pump, the combination of an internal working surface upon a fixed part with openings to permit passage of fluid to be pumped, an external working surface upon another fixed part, a hollow cylinder or bucket fitted upon the said external working surface and in the said internal working surface to work on and in such surfaces respectively and with openings to allow fluid to enter it and means to allow fluid pumped to issue from the interior of such cylinder, substantially as hereinbefore described.

3. In a double-acting pump, the combination of an internal working surface upon a fixed part with openings to permit passage of fluid to be pumped, an external working surface upon another fixed part, a hollow cylinder or bucket fitted upon the said external

working surface and in the said internal working surface to work on and in such surfaces respectively and with openings to come opposite those of the internal working surface to allow fluid to enter it and means to allow fluid pumped to issue from the interior of such cylinder or bucket, substantially as hereinbefore described.

4. In a double-acting pump, the combination of an internal working surface upon a fixed part adapted to permit passage of fluid to be pumped at more than one part of its internal surface, an external working surface upon another fixed part, a hollow cylinder or bucket fitted upon the said external working surface and in the said internal working surface to work on and in such surfaces respectively and adapted to allow at part of its movement the entrance of fluid from one part of the said internal working surface and means to allow fluid pumped to issue from the interior of such cylinder or bucket, substantially as hereinbefore described.

5. In a double-acting pump, the combination of an internal working surface upon a fixed part adapted to permit passage of fluid to be pumped at two distinct parts of its internal surface, an external working surface upon another fixed part, a hollow cylinder or bucket fitted upon the said external working surface and in the said internal working surface to work on and in such working surfaces respectively and adapted to allow at one part of its movement the entrance of fluid from one part of the said internal working surface and means to allow fluid pumped to issue from the interior of such cylinder or bucket, substantially as hereinbefore described.

6. In a double-acting pump, the combination of an internal working surface upon a fixed part with openings to permit passage of fluid to be pumped at more than one part of its internal surface, an external working surface upon another fixed part, a hollow cylinder or bucket fitted upon the said external working surface and in the said internal working surface to work on and in such surfaces respectively and with openings adapted to allow at part of its movement the entrance of fluid from one part of the said internal working surface and means to allow fluid pumped to issue from the interior of such cylinder or bucket, substantially as hereinbefore described.

7. In a double-acting pump, the combination of an internal working surface upon a fixed part with openings to permit passage of fluid to be pumped at two distinct parts of its internal surface, an external working surface upon another fixed part, a hollow cylinder or bucket fitted upon the said external working surface and in the said internal working surface to work on and in such surfaces respectively and with openings adapted to allow at part of its movement the entrance of fluid

from one part of the said internal working surface and means to allow fluid pumped to issue from the interior of such cylinder or bucket, substantially as hereinbefore described.

8. In a double-acting pump, the combination of an internal working surface upon a fixed part adapted to permit passage of fluid to be pumped at more than one part of its internal surface means to separate into distinct currents the fluid to be pumped on its way to the places of passage through the said internal working surface, an external working surface upon another fixed part, a hollow cylinder or bucket fitted upon the said external working surface and in the said internal working surface to work on and in such surfaces respectively and adapted to allow at part of its movement the entrance of fluid from one part of the said internal working surface and means to allow fluid pumped to issue from the interior of such cylinder or bucket, substantially as hereinbefore described.

9. In a double-acting pump, the combination of an internal working surface upon a fixed part adapted to permit passage of fluid to be pumped at two distinct parts of its internal surface, a partition to separate into distinct currents the fluid to be pumped on its way to the places of passage through the said internal working surface, an external working surface upon another fixed part, a hollow cylinder or bucket fitted upon the said external working surface and in the said internal working surface to work on and in such surfaces respectively and adapted to allow at part of its movement the entrance of fluid from one part of the said internal working surface and means to allow fluid pumped to issue from the interior of such cylinder or bucket, substantially as hereinbefore described.

10. In a double-acting pump the combination of an internal working surface upon a fixed part with openings to permit passage of fluid to be pumped at more than one part of its internal surface, means to separate into distinct currents the fluid to be pumped on the way to the said openings, an external working surface upon another fixed part, a hollow cylinder or bucket fitted upon the said external working surface and in the said internal working surface to work on and in such surfaces respectively and with openings adapted to allow at part of its movement the entrance of fluid from one part of the said internal working surface and means to allow fluid pumped to issue from the interior of such cylinder or bucket, substantially as hereinbefore described.

11. In a double-acting pump, the combination of an internal working surface upon a fixed part with openings to permit passage of fluid to be pumped at two distinct parts of its internal surface, a partition to separate into distinct currents the fluid to be pumped on

the way to the said openings, an external working surface upon another fixed part, a hollow cylinder or bucket fitted upon the said external working surface and in the said internal working surface to work on and in such surfaces respectively and with openings adapted to allow at part of its movement the entrance of fluid from one part of the said internal working surface and means to allow fluid pumped to issue from the interior of such cylinder or bucket, substantially as hereinbefore described.

12. In a double-acting pump, the combination of an internal working surface upon a fixed part adapted to permit passage of fluid to be pumped at more than one part of its internal surface, means to separate into distinct currents substantially of gas or liquid the fluid to be pumped on its way to the places of passage through the said internal working surface, an external working surface upon another fixed part, a hollow cylinder or bucket fitted upon the said external working surface and in the said internal working surface to work on and in such surfaces respectively and adapted to allow at part of its movement the entrance of fluid from one part of the said internal working surface and means to allow fluid pumped to issue from the interior of such cylinder or bucket, substantially as hereinbefore described.

13. In a double-acting pump, the combination of an internal working surface upon a fixed part adapted to permit passage of fluid to be pumped at two distinct parts of its internal surface, a partition to separate into distinct currents substantially of gas and liquid the fluid to be pumped on its way to the places of passage through the said internal working surface, an external working surface upon another fixed part, a hollow cylinder or bucket fitted upon the said external working surface and in the said internal working surface to work on and in such surfaces respectively and adapted to allow at part of its movement the entrance of fluid from one part of the said internal working surface and means to allow fluid pumped to issue from the interior of such cylinder or bucket, substantially as hereinbefore described.

14. In a double-acting pump, the combination of an internal working surface upon a fixed part with openings to permit passage of fluid to be pumped at more than one part of its internal surface, means to separate into distinct currents of gas and liquid the fluid to be pumped on the way to the said openings, an external working surface upon another fixed part, a hollow cylinder or bucket fitted upon the said external working surface and in the said internal working surface to work on and in such surfaces respectively and with openings adapted to allow at part of its movement the entrance of fluid from one part of

the said internal working surface and means to allow fluid pumped to issue from the interior of such cylinder or bucket, substantially as hereinbefore described.

- 5 15. In a double-acting pump, the combination of an internal working surface upon a fixed part with openings to permit passage of fluid to be pumped at two distinct parts of its internal surface, a partition to separate into 10 distinct currents of gas and liquid the fluid to be pumped on the way to the said openings, an external working surface upon another fixed part, a hollow cylinder or bucket fitted upon the said external working surface and 15 in the said internal working surface to work on and in such surfaces respectively and with openings adapted to allow at part of its movement the entrance of fluid from one part of the said internal working surface and means 20 to allow fluid pumped to issue from the interior of such cylinder or bucket substantially as hereinbefore described.

16. In a double-acting pump, the combination with a pump-casing furnished within 25 with an internal working surface adapted to permit passage of fluid to be pumped, a fixed cylinder within the said pump-casing and furnished with an external working surface, a hollow cylinder or bucket adapted to allow 30 fluid being pumped to enter it, fitted and made to work externally against the internal working surface within the pump-casing and internally against the external working surface of the said fixed cylinder, substantially as hereinbefore described.

17. In a double-acting pump, the combination of a pump-casing furnished within with an internal working surface with openings to permit passage of fluid to be pumped, a fixed 40 cylinder within the said pump-casing and furnished with an external working surface and a hollow cylinder adapted to allow fluid being pumped to enter it and a hollow cylinder or bucket fitted and made to work externally against the internal working surface within the pump-casing and internally against the external working surface of the said fixed cylinder, substantially as hereinbefore described.

18. In a double-acting pump, the combination of a pump-casing furnished within with an internal working surface adapted to permit passage of fluid to be pumped, a fixed cylinder within the said pump-casing and furnished with an external working surface and a hollow 50 cylinder or bucket with openings to allow the fluid being pumped to enter it, fitted and made to work externally against the internal working surface within the pump-casing and internally against the external surface of the said fixed cylinder, substantially as hereinbefore described.

19. In a double-acting pump, the combination of a pump-casing furnished within with an internal working surface adapted to permit 65 passage of fluid to be pumped, a fixed cylinder

within the said pump-casing and furnished with an external working surface and a hollow cylinder or bucket with an inlet to allow fluid to enter it fitted and made to work externally against the internal working surface 70 within the pump-casing and internally against the external surface of the said fixed cylinder, substantially as hereinbefore described.

20. In a double-acting pump, the combination of a pump-casing adapted to admit the 75 fluid to be pumped, means to divide into distinct currents, substantially gaseous and liquid respectively, the fluid to be pumped as it enters the said casing an internal working surface within the said casing adapted to permit the 80 passage of fluid to be pumped at distinct parts, a fixed cylinder within the said pump-casing and furnished with an external working surface and a hollow cylinder or bucket adapted to allow the fluid being pumped to enter it and 85 fitted and made to work externally against the internal working surface within the pump-casing and internally against the external working surface of the said fixed cylinder, substantially as hereinbefore described. 90

21. In a double-acting pump, the combination of a pump-casing adapted to admit the fluid to be pumped, a partition to divide into distinct currents, substantially gaseous and liquid respectively, the fluid to be pumped as 95 it enters the said casing, an internal working surface within the said casing adapted to permit the passage of fluid to be pumped at distinct parts, a fixed cylinder within the said pump-casing and furnished with an external working 100 surface and hollow cylinder or bucket adapted to allow the fluid being pumped to enter it at part of its movement from one part of the said internal working surface and fitted and made to work externally against the internal working surface within the pump-casing and internally against the external working surface of the said fixed cylinder substantially as hereinbefore described. 105

22. In a double-acting pump the combination of a pump-casing adapted to admit the fluid to be pumped means to divide into distinct currents, substantially gaseous and liquid respectively, the fluid to be pumped as it enters the said casing, an internal working surface 110 within the said casing adapted to permit the passage of fluid to be pumped at distinct parts, a fixed cylinder within the said pump-casing and furnished with an external working surface and a hollow cylinder or bucket with 115 openings to allow the fluid being pumped to enter it at part of its movement from one part of the said internal working surface and fitted and made to work externally against the internal working surface within the pump-casing and internally against the external surface of the said fixed cylinder, substantially as hereinbefore described. 120

23. In a double-acting pump, the combination of a pump-casing adapted to admit the 125

fluid to be pumped a partition to divide into distinct currents, the substantially gaseous and liquid respectively, the fluid to be pumped as it enters the said casing, an internal working surface within the said casing adapted to permit the passage of fluid to be pumped at distinct parts, a fixed cylinder within the said pump-casing and furnished with an external working surface and a hollow cylinder or bucket with openings to allow the fluid being pumped to enter it at part of its movement, from one part of the said internal working surface and fitted and made to work externally against the internal working surface within the pump-casing and internally against the external surface of the said fixed cylinder, substantially as hereinbefore described.

24. In a double-acting pump, the combination of a pump-casing divided by a perforated partition into chambers, one serving as a supply-channel for condensing liquid and the other as a condensing-chamber, and with a channel for the gaseous fluid in communication with such condensing-chamber, an internal working surface within the said casing adapted to permit the fluid to be pumped in distinct currents, substantially gaseous liquid respectively, at different parts, one in communication with the said channel for gaseous fluid and the other in communication with the condensing-chamber aforesaid, a fixed cylinder within the said pump-casing adapted to permit the passage of substantially gaseous fluid and liquid at distinct parts, a fixed cylinder within the said pump-casing and furnished with an external working surface and a hollow cylinder or bucket adapted to allow the substantially gaseous fluid to be pumped to enter it at part of its movement, from one part of the said internal working surface and fitted and made to work externally against

the internal working surface within the pump-casing and internally against the external working surface of the said fixed cylinder, substantially as hereinbefore described. 45

25. In a double-acting pump, the combination of a pump-casing divided by a perforated partition into chambers one serving as a supply-channel for the condensing liquid and the other as a condensing-chamber and with a channel for gaseous fluid in communication with such condensing-chamber, an internal working surface within the said casing adapted to permit the fluid to be pumped in distinct currents, substantially gaseous and liquid respectively, at different parts, one in communication with the said channel for gaseous fluid and the other in communication with the condensing-chamber aforesaid, a fixed cylinder within the said pump-casing with openings to permit the passage of substantially gaseous fluid and liquid at distinct parts, and a fixed cylinder within the said pump-casing and furnished with an external working surface, and a hollow cylinder or bucket with openings to allow the substantially gaseous fluid to be pumped to enter it at part of its movement from one part of the said internal working surface and fitted and made to work externally against the internal working surface within the pump-casing and internally against the external working surface of the said fixed cylinder, substantially as hereinbefore described.

In testimony that I claim the foregoing as my invention I have signed my name, in presence of two witnesses, this 10th day of April, 1905.

STANISLAS ZYLBERLAST.

Witnesses:

HOWARD CHEETHAM,
RUTH MAGDALENE WILSON.
